CLAIM

The ornamental design of a utility knife, as shown and described.

DESCRIPTION

FIG. 1 is a perspective view of a utility knife showing my new design;

FIG. 2 is a top plan view thereof;

FIG. 3 is a right side elevation view thereof;

FIG. 4 is a front elevation view thereof;

FIG. 5 is a rear elevation view thereof;

FIG. 6 is bottom plan view thereof;

FIG. 7 is a left side elevation view thereof;

FIG. 8 is a right side elevation view thereof in a partially folded position; and,

FIG. 9 is a side view showing the knife in a fully folded position.

The broken line portions of the disclosure are included for the purpose of illustrating environmental structure that form no part of the claimed design.

1 Claim, 4 Drawing Sheets
